FAN

Roland L. Lincoln, Duxbury, Mass., assignor to
 B. F. Sturtevant Company, Hyde Park, Boston,
 Mass.

Application September 28, 1944, Serial No. 556,107

1. Claim. (Cl. 230—114)

This invention relates to methods of and apparatus for controlling the volume of air moved by centrifugal fans.

As discussed in the H. F. Hagen U. S. Patent No. 1,846,863, it is desirable to operate a centrifugal fan at constant speed and to vary the volume of air moved by the fan by varying the spin velocity of the air entering the fan, in the direction of rotation of the fan blades.

The air leaving the blades of axial flow fans, usually referred to as propeller fans, spins in the direction of rotation of the fan blades, and this invention utilizes this effect by placing a propeller fan in the inlet of a centrifugal fan and varying the spin from the propeller fan for varying the air volume moved by the centrifugal fan. The propeller fan used is one which has the characteristics of moving a relatively small volume of air axially but adding considerable spin to the air drawn through it by the centrifugal fan.

An object of the invention is to vary the volume of air moved by a centrifugal fan by varying the spin in the air from a propeller fan in the inlet thereof.

The invention will now be described with reference to the drawing, of which:

Fig. 1 is a sectional view of a combined centrifugal and propeller fan embodying this invention, the speed of the propeller fan being adjustable, and

Fig. 2 is a sectional view of a combined centrifugal and propeller fan embodying this invention, the axial position of the propeller fan in the inlet of the centrifugal fan being adjustable.

The fan illustrated by Fig. 1 is a centrifugal fan similar to that disclosed by the H. F. Hagen U. S. Patent No. 2,117,416 and differs therefrom only by the inclusion in its inlet of a belt driven propeller fan and the provision of a variable speed motor for rotating the propeller fan.

Referring now to Fig. 1, the casing 16 which is the usual scroll shaped casing has mounted therein the centrifugal fan wheel 11 rotatably mounted on the shaft 12. The wheel 11 has the blades 13 attached to the side plate 14 and the back plate 15. The shaft 12 is adapted to be rotated by an external motor which is not illustrated. The curved inlet plate 16 attached at 17 to the casing 10 provides a converging inlet passage into the wheel 11.

The propeller fan 18 has the bearing 19 which is rotatably mounted on the shaft 12 whereby the propeller fan 18 can be rotated independently of the centrifugal fan wheel 11. The bearing 19 has attached thereto the pulley 20 which is rotated by the electric motor 21 through the motor pulley 22 and the belt 23.

The motor 21 has the usual speed control 24

which varies the motor speed by varying the resistance in the motor field circuit.

In the operation of the embodiment of the invention illustrated by Fig. 1, the centrifugal fan wheel is operated at constant speed. When the maximum air volume is desired, the propeller fan 18 is not rotated or is rotated at such a low speed that it has substantially no effect on the air. When reduced air volumes are desired, the speed of the propeller fan 18 is increased. The spin given the air increases conformably with the increase in speed and the volume of air delivered by the fan decreases conformably with the increase in spin.

The embodiment of the invention illustrated by Fig. 2 is similar to that of Fig. 1 except that the propeller fan 18 is mounted in the axially extending, cylindrical inlet passage 25 and is attached to the hub 26 which is keyed to rotate with, while 10 slidably movable axially on, the axially extending inner portion 28 of the fan pulley 27 which is journaled for rotation on the shaft 12. The lever 30 has the pins 31 which slide in the slot 37 in the hub 26, and is pivoted at 32 to a wall 20 of the inlet passage, and is connected through 25 the pivoted links 33 and 34 to the control lever 35.

The spin imparted to the air entering the centrifugal fan wheel is varied by moving the lever 35 along the calibrated segment 36. Movement of the lever 35 results in the axial displacement 30 of the propeller fan with reference to the centrifugal fan wheel. As the propeller fan is moved closer to the centrifugal fan wheel, the spin effect is increased, and as the propeller fan is moved further from the centrifugal fan wheel, the spin effect is decreased. This because the spin begins to straighten out as soon as it leaves the propeller fan. Thus as the control arm 35 is adjusted to decrease the distance between the propeller fan and the centrifugal fan wheel, the spin in the air entering the centrifugal fan wheel increases, and the volume of air delivered by the centrifugal fan decreases conformably.

What is claimed is:

45 A fan assembly comprising in combination, a fan wheel, means forming a cylindrical air inlet passage extending axially to the inlet of said wheel, a shaft for rotating said wheel, a hub rotatably mounted around said shaft in said passage, propeller blades attached to said hub, means for rotating said hub for imparting a spin by said blades to the air entering the inlet of said wheel, and means for slidably positioning said hub along said shaft for varying the distance of 50 said blades from said wheel for varying the degree of spin in the air entering said wheel.
